UNITED STATES PATENT OFFICE.

ALFRED G. STOKES, OF BELOIT, WISCONSIN, ASSIGNOR TO FAIRBANKS, MORSE & CO., OF CHICAGO, ILLINOIS, A CORPORATION OF ILLINOIS.

STEAM-ACTUATED VALVE FOR ENGINES.

No. 899,849.

Specification of Letters Patent. Patented Sept. 29, 1908.

Application filed February 25, 1907. Serial No. 359,143.

To all whom it may concern:

Be it known that I, ALFRED G. STOKES, a citizen of the United States of America, residing at Beloit, in the county of Rock and State of Wisconsin, have invented certain new and useful Improvements in Steam-Actuated Valves for Engines, of which the following is a specification, reference being had therein to the accompanying drawings.

10 My invention relates to new and useful improvements in steam engines and particularly to that type of steam engine which is adapted for use in driving feed and other pumps.

15 One object of the invention is to control both the chest piston and the cylinder or main piston by a single slide valve; another object is to prevent the sticking of the chest piston; third, to obviate dead centers; 20 fourth, to arrange the parts conveniently for inspection and lubrication; and, fifth, to secure simplicity of the entire mechanism.

25 The novel construction and arrangement of parts whereby I have attained these objects will be more fully hereinafter described and set forth in the claims.

30 In the drawings, Figure 1 shows a longitudinal vertical central section through the engine; Fig. 2 shows a horizontal section through the steam chest on line $x-x$ of Fig. 1; Fig. 3 shows a transverse vertical section on lines $y-y$ of Fig. 1; Fig. 4 shows a transverse vertical section on lines $z-z$, of Fig. 1; and Fig. 5 shows a longitudinal vertical central section through the engine with the parts 35 in the positions shown in Fig. 4.

1 is the cylinder of a steam pumping engine, preferably connected by a cradle 6 to the pump cylinder 7. In the steam cylinder 40 is the main piston 2, having a piston rod 3 connected to the pump piston.

45 The steam chest 4 is suitably mounted on the cylinder 1, and in the chest is a chest piston 5 having a stem 8 projecting through the end of the chest.

50 The main steam inlet port 9 communicates with the chamber 10 in the steam chest, while the exhaust chamber 11 communicates with the main exhaust port 12. Passages 13 lead from opposite ends of the cylinder to points adjacent to the steam chamber 10 and exhaust chamber 11 and smaller passages 14 lead from opposite ends of the steam chest to points adjacent to steam chamber 10 and exhaust chamber 11.

In the steam chest is a slide valve 15 having a groove in its top for engagement with lug 16 suitably secured to the chest piston, as by the screws 17. This valve has notches 18 in its sides arranged to expose the ends of 60 passages 14 to the pressure of steam chamber 10 in certain positions of the valve and in its lower face is a port or concavity 19 of sufficient size to connect the exhaust chamber with either of the passages 13 in different 65 positions of the valve. This valve is arranged to expose the passages 13 to steam pressure in the chamber 10 alternately when reciprocated longitudinally of the steam chest. A bifurcated cam 20 is secured to the 70 stem 8 and is arranged to be engaged by an anti-friction roller 21 journaled on a pin 22 projecting from the side lever 23 fulcrumed on the projection 24 on the cradle 6. The lower end of the side lever 23 is pivotally 75 connected to the crosshead 25 on the piston rod 3 through a pivotal link 26.

On the stem 8 is a stop-collar 27 arranged to be engaged alternately with the end of the cam 20, which also serves as a stop-collar, by 80 the sliding sleeve 28 actuated by the upper end of the side lever 23 through the pivotal link 29.

The operation of the construction above described is as follows: Steam having been 85 admitted to the chamber 10 through the port 9, it will be seen that one of the passages 13 or one of the passages 14 is exposed to pressure from said chamber in every position of the chest piston and valve, thus avoiding 90 dead centers. Assuming the parts to be in the positions shown in Fig. 1, the steam will pass through the rear passage 13 and carry the piston 2 in the direction of the arrow until the roller 21 strikes the upper furcation of 95 the cam 20. This will rock the chest piston 5 and carry the valve 15 transversely to the position shown in Fig. 2, thus bringing one of the notches 18 in line with the end of the forward passage 14, as shown. In the further 100 movement of the piston 2, the sleeve 28 will strike the end of the cam 20 and retract the chest piston 5, until the notch 18 exposes the forward passage 14 to the pressure in chamber 10 and one of the extensions 30 of the 105 concavity 19 in the lower face of the valve 15 connects the rear passage 14 with the exhaust chamber 11, as shown in Fig. 4. In this position, it will be seen that the slight retraction of the chest piston has caused the valve 110

15 to partially close the passages 13, as shown in Fig. 5. This partial closing of the main ports just previous to the end of the stroke eases the action of the pump and high speed is permitted without slamming the pump check valves. The retraction of the valve and exposure of forward passage 14 to pressure and rear passage 14 to exhaust immediately causes the complete retraction of the chest piston and the throwing over of the valve 15, and at the other end of the stroke the same sequence of operations is accomplished, the roller 21 striking the lower furcation of cam 20 and the sleeve 28 striking stop 15 collar 27.

From the above description of the operation, it will be seen that the reciprocation of the chest piston controls the main or cylinder piston and the cylinder piston in its reciprocation controls the chest piston.

The slight rocking of the chest piston entirely obviates sticking and it will be seen that all parts are simple and conveniently arranged for inspection and lubrication.

25 What I claim as my invention is:

1. In a steam engine, the combination with a cylinder and a piston therein, of a steam chest, a chest piston therein, a valve connected to said chest piston and arranged 30 to be longitudinally reciprocated thereby to control said cylinder piston and means operable by said cylinder piston for rocking said chest piston to transversely reciprocate said valve and for reciprocating said chest piston 35 to longitudinally reciprocate said valve, said transverse and longitudinal reciprocation controlling said chest piston.

2. In a steam engine, the combination with a cylinder, a piston therein, a steam 40 chest, a piston therein, a valve adapted to be longitudinally reciprocated by said chest piston in a horizontal plane to control the movement of said cylinder piston, and means operable by said cylinder piston for shifting 45 said valve transversely in a horizontal plane and for reciprocating said chest piston.

3. In a steam engine, the combination with a cylinder having passages communicating with its opposite ends and a piston in 50 said cylinder, of a steam chest having passages communicating with its opposite ends, a chest piston in said chest, a valve connected to said chest piston and controlling said cylinder and steam chest passages, and means 55 for transversely and longitudinally reciprocating said valve in a horizontal plane near the end of each stroke of said cylinder piston for opening and closing said steam chest passages and for partially closing said cylinder 60 passages, for the purpose described.

4. In a steam engine, the combination with a cylinder and a piston therein, of a steam chest, a chest piston therein, a valve arranged to be transversely and longitudinally reciprocated by said chest piston in a

horizontal plane for controlling said cylinder piston, a piston rod for said cylinder piston, a stem on said chest piston, and connections between said rod and stem for rocking and reciprocating said stem, for the purpose de- 70

5. In a steam engine, the combination with a cylinder and a piston therein, of a steam chest and a piston therein, of a valve, means controlled by said cylinder piston for imparting an oscillating and longitudinally reciprocating movement to said chest piston, and connections between said chest piston and valve whereby said oscillating and longitudinally reciprocating movement of said chest 75 piston imparts to said valve a transverse and longitudinal reciprocation in a horizontal plane.

6. In a steam engine, the combination with a cylinder and a piston therein, of a steam chest and a piston therein, a valve, said chest piston and said valve being provided one with a cylindrical lug and the other with a correspondingly shaped groove adapted to coöperate therewith, and connections 80 between said cylinder piston and chest piston for imparting a rocking and reciprocating movement to said chest piston.

7. In a steam engine, the combination with a cylinder and a piston therein, of a steam chest and a piston therein, of a valve, a cylindrical lug secured to the under side of said chest piston and engaging a correspondingly shaped groove in the upper side of said valve, and connections between said cylinder 95 piston and chest piston for imparting a rocking and reciprocating movement to said chest piston.

8. In a steam engine, the combination with a cylinder having passages communicating with its opposite ends, a piston in said cylinder, a steam chest having passages communicating with its opposite ends, a piston in said chest adapted for a reciprocating and oscillating movement, a slide valve 100 adapted for transverse and longitudinal movement in one plane and having a cavity therein controlling the passages to the cylinder and notches in its sides controlling the passages to the steam chest, a valve stem extending from said chest piston, a cam carried thereby, a rocker arm operated from the piston rod of the engine and adapted to engage said cam, tappets carried by the valve stem, a cross head slidably mounted on the valve 110 stem intermediate said tappets, and a link connecting said cross head and rocker arm.

9. In a direct acting engine, a cylinder, a piston therein, a steam chest, a piston therein adapted for a reciprocating and oscillating movement, a valve operable by said chest piston and movable longitudinally and transversely to control the passage of steam to the opposite ends of said cylinder and steam chest, and means for operating said valve, 115

- said means including, a valve rod extending from the chest piston, a cam on said valve rod, a rocker arm pivoted to the frame of the engine and adapted to be operated by the main piston rod, a roller on said rocker arm adapted to engage the cam on the valve rod to partially rotate the same and lock it in position after its rotary motion is completed, tappets on the valve rod, a cross head loosely mounted on the valve rod intermediate said tappets, and means for actuating said cross head from the main piston rod.
10. In a steam engine, the combination with a cylinder and a piston therein, a steam chest and a piston therein adapted for a reciprocating and oscillating movement, a flat valve seat provided with ports therein communicating with opposite ends of the cylinder and steam chest, a valve movable in two directions on said valve seat and controlling the ports therein, said valve being operatively connected to the piston in the steam chest, and means for operating said steam chest piston, said means including a valve stem extending from the steam chest piston, a cam thereon, and a rocker arm actuated by the piston rod of the engine and adapted to coöperate with said cam, said cam and rocker arm forming a locking device preventing undue shifting of the valve while being thrown finally by steam.
11. In testimony whereof I affix my signature in presence of two witnesses.
- ALFRED G. STOKES.
